ROTARY MACHINE

Frederic W. Hild, Los Angeles, Calif., assignor to
United States Heat Treating Company, San An-
tonio, Tex., a corporation of Texas

Application March 5, 1925, Serial No. 13,049

41 Claims. (Cl. 255—23)

This invention relates to the rotary system of drilling oil wells, and it particularly appertains to a rotary machine employed in this system.

In the drilling of oil wells by the rotary system, it is common to secure a cutter at the lower end of a drill pipe, which drill pipe extends upwardly through the well to the surface of the ground. A swivel head is attached at the upper end of the drill pipe and a travelling block is connected thereto, this travelling block serving to support the drill pipe. A high pressure pump is connected to the swivel head by means of a stand pipe and a hose, this pump being for the purpose of supplying rotary mud to the cutter or rotary bit during drilling operations. The upper end of the drill pipe is generally provided in the form of a square or fluted drill stem which extends through a rotary table of a rotary machine mounted on the floor of a derrick. This rotary table is rotated by mechanism of the derrick and rotates the drill pipe, thus rotating the rotary bit and thus drilling the well.

It is an object of my invention to provide a rotary machine of this character in which the bearings and gears will be thoroughly lubricated. The base and table of the rotary machine are so constructed as to form an entirely closed oil chamber. In this oil chamber are situated bearings for rotatably supporting the drill table and also the gears whereby the rotary table is rotated. When the machine is in operation, one of the gears whereby the table is rotated splashes in an oil body inside the oil chamber. Oil is splashed or carried by the various moving parts, thus thoroughly lubricating the gears and thoroughly lubricating the bearings. The table and base are so constructed as to entirely prevent dust from entering the oil chamber.

It is another object of my invention to provide a novel form of baffle member which arrests the leakage of oil from the oil chamber. The base of the rotary machine provides inner and outer upwardly extending annular walls and the table of the rotary machine provides an inner annular extension which extends inside the annular wall of said base and an outer lip which extends outside the outer annular wall of said base. The baffle plate is placed at the upper face of the outer annular wall of the base member. A portion of this baffle plate extends inwardly from the outer annular wall to a point above the outer part of a bevel gear mounted on the rotary table. Oil which is splashed when the machine is in operation strikes against the lower face of the bevel member and is prevented from seeping between

the upper face of the outer annular wall of the base and the outer lip of the table. The inner diameter of the outer wall of the base and the outer diameter of the bevel gear mounted on the table are of only a slight difference in size. The 5 baffle plate is made from a semi-resilient material. When the table is installed in place, the inner portion of the baffle plate is engaged by the periphery of the bevel gear and is swung from a normal position to allow the bevel gear to pass 10 thereby. When the gear is passed by the baffle plate, the baffle plate will, due to its resiliency, swing outwardly into a normal position so as to extend over the outer portion of the bevel gear.

It is also an object of my invention to provide 15 a novel form of hold-down ring for a rotary machine of this character. I provide a complete annular ring which is secured to the base of the machine. This annular ring is provided with a bearing race and between this hold-down ring 20 and a complementary race provided by a part of the table are placed balls. The hold-down ring is adjustable so that any up and down movement in the table may be eliminated. It is present practice to provide a hold-down ring which 25 has a flange engaging a face of the rotary table. The flange is adjusted relative to the face of the table so that there is a slight space therebetween due to the fact that if there were engagement between these parts, there would be an excessive 30 frictional engagement. Because of this space, there is always an up and down movement of the table relative to the base. By providing the bearing arrangement for a hold-down ring, it is possible to acquire a very accurate adjustment 35 without appreciable friction and thus entirely eliminate up and down movement in the table as well as radial vibration of the table.

It is another object of my invention to provide 40 in a rotary table of the character mentioned, a novel form of nonadjustable pinion housing which allows for the insertion of a drive pinion into the oil chamber, and which also carries bearings for supporting a pinion shaft, with the end closure for the housing about the shaft to 45 retain the oil within the device.

Rotary machines are not only used for the purpose of rotating the drill pipe during the drilling of a well, but they are also employed during the installing and removing of stands of the drill 50 pipe. One method of making and breaking joints of the stands is by securing the lower portion of the pipe against rotation and rotating a top stand, this rotation of the top stand being usually 55 accomplished by the rotary table of the rotary

machine. Another method of making and breaking joints is by rotating the lower part of the drill pipe and locking an upper stand thereof against rotation.

5 When the joints are made by the method of rotating a top stand of the drill pipe, there is a great danger of the joints being made too tight and destroying the threads. Any galling of the threads of these joints reduces the dependability 10 and life of the joints; however, the joints are very satisfactorily broken by this method of rotating a top stand of the drill. In the effort to prevent the screwing of these joints too tight, various devices have been made which are arranged for 15 installation on the tongs or on a post which extends from the rotary machine to the tongs for rotating the top stand. These devices, however, have not proved very satisfactory.

It is an object of my invention to incorporate 20 in a rotary machine of the character mentioned a means for positively restraining rotation in the lower portion of a string of drill pipe during the breaking of a joint, and for restraining rotation in the lower pipe of a string of drill 25 pipe until a certain force is exerted against this lower pipe during the tightening of a joint. I provide the rotary machine with a special form of slip ring which carries slips for gripping the lower part of the drill pipe, this rotary machine 30 being especially formed for the reception of said slip ring. The slip ring is provided with a brake drum portion having a pair of shoulders formed thereon. A pair of brake shoes is arranged to engage said shoulders during the breaking of a 35 joint, thus positively restraining the lower part of the drill pipe from rotation. During the tightening of a joint, the slip ring is frictionally restrained from rotation by engagement of the brake drum by said brake shoes. When a certain 40 amount of rotative force of the upper stand of drill pipe is transferred to the lower portion of the drill, frictional engagement between the brake drum and the brake shoes is overcome and the lower part of the drill pipe will rotate with the 45 upper stand. It is obvious that this arrangement will prevent the parts of said joints from being screwed too tightly together when making a joint.

It is another object of my invention to provide 50 a means for adjusting the pressure of a frictional engagement between the brake shoes and the brake drum, thus allowing a rotation of the lower part of the drill pipe in any desired rotational force.

55 It is also an object of my invention to provide a slip ring and braking construction which is of such a character that it may remain in place during the operation of the rotary machine when drilling the well. This construction is of such a 60 character that it will offer no resistance to the various parts of the rotary machine during this time.

In the making and breaking of joints by a rotation of the lower part of the drill pipe, this 65 lower part is generally engaged and rotated by the rotary table of the rotary machine. The upper stand of drill pipe is held against rotation by a suitable device such as pipe tongs.

It is a still further object of my invention to 70 provide in a rotary machine of this character a special form of slip ring drive bushing which is adapted for use in conjunction with the slip ring brake arrangement of my invention.

Other objects and the especial advantages of 75 this invention will be made evident hereinafter.

Referring to the five sheets of drawings which are for illustrative purposes only.

Fig. 1 is a sectional view of a rotary machine embodying the features of my invention, this section being taken through a rotary table of the 5 machine substantially as indicated by the line 1—1 of Fig. 2.

Fig. 2 is a plan view of one end of the rotary machine, this view showing a table of the rotary machine and being partially sectioned to clearly 10 show certain of the features of this invention.

Fig. 3 is a view taken substantially as indicated by the arrow 3 of Fig. 2, this view showing a novel form of pinion housing provided by the 15 invention.

Fig. 4 is an enlarged fragmentary view clearly illustrating the construction and operation of a novel form of baffle plate provided by this invention.

Fig. 5 is a sectional view taken on the line 5—5 20 of Fig. 2, this view clearly showing the construction of a slip ring and braking arrangement of my invention.

Fig. 6 is a partial plan view of Fig. 5.

Fig. 7 is a section taken substantially as indicated by the line 7—7 of Fig. 5.

Fig. 8 is a plan view of the rotary table showing a slip ring drive bushing of my invention in use.

Fig. 9 is a section taken as indicated by the line 9—9 of Fig. 8.

Referring to the drawings, a rotary table having the features of my invention has a base frame 11 which is arranged to be supported by suitable planks 12. At one end of the base 11 is a base opening 13 which is surrounded by an 35 inner annular upwardly extending wall 15. Extending concentrically around the wall 15 is an upwardly extending outer annular wall 16. Between the walls 15 and 16 is a bottom 17. A lower portion 19 of an inner extension 20 of a rotary 40 table 21 extends inside the upper end 23 of the inner annular wall 15. An outer lip 25 extends downwardly around the upper portion 26 of the outer annular wall 16. A top 27 of the table 21 extends between the annular projection 20 and 45 the lip 25 of the table 21. The table 21 and the base 11 cooperate to provide a completely closed annular oil chamber 28.

An inner face 31 of a lower bearing race 32 is forced upon an outer face 33 of the upper portion 23 of the inner annular wall 15 to the extent that a lower face 34 thereof engages with an annular face 35 provided by the bottom 17 inside the oil chamber 28. Suitable shims 37 may be placed between the faces 34 and 35 to adjust 55 the lower bearing race 32 to the proper position. An inner face 39 of an upper bearing race 40 is pressed upon an outer face 41 of the annular projection 20 to the extent that an upper face 42 thereof engages the face 43 provided by the 60 table 21. A series of ball bearings 45 is placed in channels 46 and 47 of the bearing races 40 and 32, respectively. The bearing races 32 and 40 and the ball bearings 45 are located inside the oil chamber 28 and serve to rotatably support 65 the rotary table 21.

A completely annular race portion 48 of a hold-down ring 49 extends into the groove of the table formed above an upper, outer face 50 of the upper bearing race 40. Between the upper 70 face 50 of the race 40 and a face 52 of the race portion 48 of the hold-down ring 49, is arranged a series of balls 53. A flange portion 55 of the hold-down ring 49 is bolted to an annular face 56 of the bottom 17 of the base 11 by means of 75

bolts 57. Shims 58 are placed between the face 56 and the flange 55 for adjusting the hold-down ring 49 to a proper position. This hold-down ring 49 is provided for the purpose of eliminating any up and down movement in the table 21. By incorporating the ball and race arrangement shown in a hold-down ring, it is possible to obtain a very accurate adjustment so that up and down movement may be entirely eliminated without incurring a considerable friction. By providing the hold-down ring completely annular, the efficiency thereof is assisted.

On a cylindrical face 60 of the table 21 is forced a bevel gear 61, this bevel gear 61 being rigidly retained in place upon the face 60 so as to engage an upper annular shoulder 62. As clearly shown in Figs. 1 and 2, the chamber 28 is enlarged at 65 for the reception of a pinion gear 66 which is arranged to engage and drive the bevel gear 61. The annular face 56 and the flange portion 55 of the hold-down ring 49 terminate at either side of this enlargement 65, as indicated at 67, to provide room for the pinion gear 66. The pinion gear 66 is secured to the end of a shaft 68 which extends outwardly from the oil chamber 28 through a pinion housing 69. This end of the shaft 68 is supported by a roller bearing 71 which is supported by a cylindrical wall 72 of the pinion housing 69. The opposite end of this shaft 68, as shown in Fig. 8, is rotatably supported in a bearing 75. The shaft 68 is driven by any suitable means such as a sprocket wheel 76 shown in Fig. 8, which may be rotated by a sprocket chain, not shown.

With reference to Figs. 1, 2 and 3 the bearing housing 69 has an outer cylindrical wall 78 which extends into a cylindrical opening 79 formed in the outer wall 16 of the base 11. The pinion housing 69 is secured in place by bolts 80 which extend through a radial flange 81 thereof. The cylindrical opening 79 in the wall 16 is slightly larger than the periphery of the pinion gear 66. The pinion gear 66 is installed in place in the enlarged portion 65 of the chamber 28 through the opening 79, after which the pinion housing 69 is secured in place, as shown in the drawings. The outer enclosing plate of the bearing housing 69 around the shaft has a lesser diameter than the overall diameter of the bearing, thereby retaining lubricant which might otherwise escape.

The opening 79 also provides access to the chamber 28 so that the balls 53 of the hold-down ring arrangement may be installed previous to the installing of the pinion gear 66. All of the bolts 57 which secure the hold-down ring 49 in place are loosened so that the ring may be lifted and may be tightened or otherwise adjusted from the outside of the enclosed portion as the nuts on these bolts 57, as seen in Fig. 1, are on the outside. Spacers 83 which space the balls 53 are made in sections 84 as clearly shown in Fig. 2. These sections are of such a size that they may be inserted through the opening 79 and into place between the race 48 and the face 50 of the upper bearing race 40. After all of the sections 84 of the spacers 83 are arranged in place, the bolts 57 are tightened, thus securing the hold-down ring 49 in its proper position. After this installation, the pinion 66 is installed.

As clearly shown in Fig. 4 an annular baffle plate 88 is secured to an upper annular face 89 of the outer annular wall 16. A baffle portion 90 of the plate 88 extends inwardly inside the inner face 91 of the wall 16, this portion 90 extending above the outer portion of the bevel

gear 61. As is evident from Fig. 4, the inner face 91 and the periphery 93 of the gear 61 are nearly the same size. To permit the passing of the bevel gear 61 by the baffle plate 88, it is necessary to construct the baffle plate 88 of a semi-resilient material. When the table 21 is installed, it is first moved into position above its proper position, as indicated by the dotted lines 95 of Fig. 4. The complete table 21 is then lowered. The periphery 93 of the bevel gear 61 engages the baffle portion 90 of the baffle plate 88, swinging it into the position shown by the dotted lines 96 of this figure. When the gear 61 has moved past the baffle plate 88, the baffle portion 90 thereof due to its resiliency, will swing into the position shown in full lines in this figure. When in this position, the portion 90 extends over the outer portion of the bevel gear 61. When the table 21 is removed from place, the periphery 93 of the bevel gear 61 engages the portion 90 of the baffle plate 88 and swings it into the position indicated by the dotted lines 97 of Fig. 4.

If the baffle plate 88 were made of a rigid material, it would be necessary to make the difference in size of the face 91 and the periphery 93 much greater than is necessary with a semi-resilient baffle plate as provided by my invention. By the provision of this baffle plate 88, it is possible to make these portions 91 and 93 of substantially the same size, thus saving considerable space.

The enlarged portion 65 of the chamber 28 is filled with oil as indicated at 98 in Fig. 1. When the rotary machine is in operation, the oil is splashed by the pinion gear 66. This splashing carries oil to the bevel gear 61 and to the supporting bearing of the machine, to the hold-down bearing. This splash system of lubrication thoroughly lubricates these bearings as well as lubricating the pinion and the bevel gear. The baffle plate 88 prevents a leakage between the wall 16 and the lip 25. Any oil which is splashed in this vicinity strikes against a lower face of the baffle portion 90 and is deflected downwardly. Any oil which strikes on the upper face of the baffle portion 90 gravitates due to the slope thereof away from the wall 16 and the lip 25 back to the lower part of the oil chamber 28.

The arrangement shown in the drawings provides a very thorough lubricating system for the various bearings and for the gears. The chamber 28 is completely closed and excludes all dirt from these moving parts. The baffle plate 88 eliminates the leakage of oil from the chamber 28 at this point. The feature of the pinion housing 69 readily permits the inserting of the balls and spacers of the hold-down arrangement, and also permits an easy installation of the pinion gear 66.

The slip ring and braking construction of my invention is clearly shown in Figs. 5, 6 and 7 of the drawings. With particular reference to these figures, a slip ring 110 rests in the opening 13 of the base 11 and an opening 111 of the table 21. An annular bevel face 113 of the slip ring 110 engages a bevel shoulder 114 which surrounds the opening 13; thus the slip ring 110 is supported in place. Slips 115 are supported by a conical inner face 116 of the ring 110, these slips 115 being adapted to engage and support a drill pipe 118 during the making and breaking of a joint.

A brake drum face 120 is provided at the lower end of the slip ring 110 between radial faces 121 and 122. The two opposing halves of the

brake drum face 120 are formed on centers which are slightly offset with respect to each other in such a manner as to form shoulders 123 which are diametrically opposed to each other. Resting against a brake drum 120 are brake shoes 125, these brake shoes 125 being hingeably secured together by flexible hinge members 127 which are pivoted together at 128. These hinge members 127 retain the brake shoes 125 in their proper positions, but due to the flexibility thereof allow these brake shoes to operate against the brake drum independently with respect to each other. Brake rods 130 extend through openings 131 in the base 11, the inner ends 135 thereof extending into outer cavities 134 formed in the brake shoes 125. The outer ends of these brake rods pivot at 136 to arms 137 of bell cranks 138, which bell cranks 138 pivot at 139 to clevises 141 of the base 11. Arms 142 of the bell cranks 138 are forked at 144 and have blocks 145 pivotally secured thereto by means of pins 146. Adjustably secured to the blocks 145 are eye-bolts 147, which eye-bolts 147 have tension springs 150 connected with eyes 151 thereof. The lower ends of the springs 150 are secured to rods 153 which are supported by brackets 154, these brackets 154 being shown as secured to planks 12 which support the base 11.

Extending upwardly from a post hole 158 formed in the rotary table 21 is a tong post 159. This tong post 159 extends upwardly into a socket 160 formed in a boss at the end of a tong lever 161 of a pair of tongs 162. The tongs 162 as shown in Fig. 5 are placed around an upper stand 163 of the string of drill pipe 118.

When the arrangement shown is employed for breaking a joint, the rotary table is rotated in the direction indicated by the arrows 164 of Figs. 6 and 7. When the rotation starts, the complete string of drill pipe 118 rotates and the slip ring 110 rotates therewith until the shoulders 123 move into engagement with end faces 165 of the brake shoes 125. This engagement positively prevents a further movement in the lower part of the drill pipe, the upper stand 163 of this drill pipe turning with the table 21, thus breaking the joint. The pressure of the shoulders 123 against the shoulders 165 of the shoes 125 is applied to the rods 130 which are very rugged and resist any rotation in the shoes 125.

As mentioned in the preamble, there is at present when using apparatus for making joints by this method great danger of making the joints too tight and ruining the threads thereof, reducing their dependability and life. My equipment is of such a character that the lower part of the drill pipe is permitted to rotate when a certain tightness of joint is obtained. The springs 150 exert a downward pull on the arms 142 of the bell cranks 138, thus forcing the rods 130 inwardly against the brake shoes 125, this in turn forcing the brake shoes 125 against the drum 120. By adjusting the relative positions of the pins 147 and the blocks 145, the pull of the springs 150 against the bell cranks 138 may be regulated; this in turn regulating the pressure of engagement between the brake shoes 125 and the brake drum 120. If desired, in place of the spring arrangement shown for forcing the shoes into engagement with the brake drum, I may provide a weight arrangement which will accomplish the same result as the construction shown.

When making a joint, the lower portion of the drill pipe is held in the same manner as when breaking a joint. The tongs 162 are placed on

the upper stand of pipe to be secured to the drill pipe, and the post 159 is extended into one of the openings 158 of the rotary table 21. The rotary table is then rotated in a direction opposite to that indicated by the arrows 164 of Figs. 6 and 7. The frictional engagement between the brake shoes 125 and the drum 120 prevents a rotation of the lower part of the drill pipe 118. As the upper stand is threaded to the lower part of the drill pipe, a frictional engagement therebetween gradually increases as the joint tightens. The rotational force of the upper stand 163 is transferred to the lower part of the drill pipe 118 in proportion to the tightness of the joint being made. It is arranged that sufficient rotational force to 15 overcome the frictional engagement between the shoes 25 and the drum 20 will be transferred to the lower part of the drill pipe when the joint has been tightened to a proper degree. When this point is reached, the force of rotation transferred to the lower part of the drill pipe by the upper stand is sufficient to overcome the friction of the engagement between the brake shoes 125 and the brake drum 120 and the lower part of the drill pipe 118 will rotate with the upper stand being secured thereto. When the ring 110 is rotated in a direction reverse to that indicated by the arrows 164, the shoulders 123 as is evident from Fig. 3, move uninterferingly inside the brake shoes 125.

During the drilling of the well, a stem drive bushing 170 may be placed in the opening 111 of the table 21 without the necessity of removing the slip ring 110 or any of the breaking parts from place as they offer no resistance to the member 170 or to the rotation of the table 21. The bushing 170 is shown installed in Figs. 1 and 2 of the drawings.

The arrangement of my invention as shown in Figs. 5, 6 and 7 will positively lock the lower part 40 of the drill pipe against rotation during the breaking of a joint and will frictionally restrain the lower part of the drill pipe from rotation during the making up of a joint until the time that a certain amount of rotational force is transferred to the lower part of the drill pipe from the upper stand being secured thereto. A screwing of the joints too tightly together and any damage caused thereby are entirely eliminated. The tightness of the joint is determined by the magnitude of the 45 force of the frictional engagement between the drum and brake shoes, which frictional engagement may be regulated to a desired point by varying the tension of the springs 150.

In Figs. 8 and 9 I illustrate the use of a slip 55 drive bushing of my invention adapted to be used in conjunction with the slip ring 110 when joints are to be broken by the method of rotating the lower part of the drill pipe while the upper stand is held non-rotatable. As clearly shown in these 60 figures, I provide a drive bushing 190 having a polygonal portion 191 and a conical portion 192. The drive bushing is placed in the opening 111 in the table 21 in such a manner that the polygonal portion 191 rests in polygonal formation 193 of the opening 111, and in such a manner that the conical portion 192 engages with a conical formation 194 of the table 21. An engagement between the polygonal portion 191 and the polygonal formation 193 serves to rotate the drive 70 bushing with the table and an engagement between the conical portion 192 and the conical formation 194 serves to support the drive bushing 190. In a central opening 195 of the drive bushing 190 is an annular wall 196 having notches 75

- 197 formed therein. The slip ring 110 has an annular shoulder 198 which engages with the upper face of the wall 196, thus supporting the slip ring 110 away from the bevel shoulder 114 of the base 11. Lugs 199 are formed on the exterior of the slip ring 110, which lugs 199 extend into the notches 197 serving as a means whereby the slip ring 110 is rotated with the drive bushing 190. These lugs 199 also serve to strengthen the slip ring 110. To permit a ready installation of the drive bushing 190, this drive bushing is made in the form of cooperating parts 202. The upper stand, in this method of breaking the joints, is held against rotation by a pair of tongs 204. The 10 rotary table is rotated in the proper direction as the drive bushing and slip ring rotate therewith. This rotates the lower section of the pipe 118, thereby breaking the joint. The slip ring and brake arrangement and drive bushing of my invention adapt the rotary table for quickly making and breaking the joints of stands of drill pipe. The joints may be readily broken and they may be readily made without danger of making the joints too tight and ruining the threads.

25 I claim as my invention:

  1. In a rotary machine of the class described, the combination of: a body, said body having inner and outer upwardly extending concentric annular walls forming an annular channel; a table carried by said body, said table having a downwardly extending annular extension and a downwardly extending annular lip, said annular extension extending inside said inner wall and said lip extending outside said outer wall, thus forming an annular oil chamber; a lower annular bearing race carried by said body; an upper annular bearing race carried by said table; ball bearings arranged between said lower and upper bearing races, whereby said table is rotatably supported; an annular hold-down ring secured to said body; and balls arranged between said hold-down ring and said upper bearing race for preventing an up or down movement in said table, said upper and lower bearing races, said ball bearings, said hold-down ring and said balls being disposed inside said oil chamber.
  2. In a rotary machine of the class described, the combination of: a body, said body having inner and outer upwardly extending concentric annular walls forming an annular channel; a table carried by said body, said table having a downwardly extending annular extension and a downwardly extending annular lip, said annular extension extending inside said inner wall and said lip extending outside said outer wall, thus forming an annular oil chamber; an annular baffle secured to the upper face of said outer annular wall; an annular bearing disposed in said annular oil chamber for rotatably supporting said table; a bevel gear on said table inside said annular oil chamber; and a pinion gear for driving said bevel gear, said pinion gear being situated inside said annular oil chamber.
  3. A combination as in claim 2 in which said bevel gear has an outer diameter which is slightly smaller than the inner diameter of said outer wall and in which said baffle extends inwardly from said outer wall and is flexible to permit the extending of said bevel gear thereby.
  4. In a rotary machine of the class described, the combination of: a body, said body having inner and outer upwardly extending concentric annular walls forming an annular channel; a table carried by said body, said table having a downwardly extending annular extension and a

downwardly extending annular lip, said annular extension extending inside said inner wall and said lip extending outside said outer wall, thus forming an annular oil chamber; an annular bearing disposed in said annular oil chamber for rotatably supporting said table; a bevel gear on said table inside said annular oil chamber; and a pinion gear for driving said bevel gear, said pinion gear being situated inside said annular oil chamber; and a pinion housing, said pinion housing being secured to said outer wall of said base for closing an opening through which said pinion is inserted into said oil chamber.

5. A combination as defined in claim 4 in which said pinion housing carries a bearing for a shaft extending from said pinion gear.

6. In a rotary machine of the class described, the combination of: a base having a base opening therethrough; a rotary table rotatably carried by said base, said rotary table having an opening therethrough which aligns with said base opening; a slip ring arranged in said openings; slips carried by said slip ring, said slips being adapted to grip a pipe; and means for positively preventing a rotation of said pipe in one direction and for retarding a rotation of said pipe in an opposite direction, said means allowing said pipe to rotate in said second mentioned direction when the resistance of said retarding means is overcome.

7. In a rotary machine of the class described, the combination of: a base having a base opening therethrough; a rotary table rotatably carried by said base, said rotary table having an opening therethrough which aligns with said base opening; a slip ring arranged in said openings; slips carried by said slip ring, said slips being adapted to grip a pipe; and means for positively preventing a rotation of said pipe in one direction and frictionally preventing a rotation of said pipe in an opposite direction.

8. In a rotary machine of the class described, the combination of: a base having a base opening therethrough; a rotary table supported by said base, said rotary table having a table opening which aligns with said base opening; a slip ring arranged in said openings; and means for positively preventing rotation of said slip ring in one direction and for frictionally preventing a rotation of said slip ring in an opposite direction.

9. In a rotary machine of the class described, the combination of: a base having a base opening therethrough; a rotary table supported by said base, said rotary table having a table opening which aligns with said base opening; a slip ring arranged in said openings; a brake drum formed on said slip ring; and brake shoes adapted to engage said brake drum so as to prevent a rotation of said brake drum.

10. In a rotary machine of the class described, the combination of: a base having a base opening therethrough; a rotary table supported by said base, said rotary table having a table opening which aligns with said base opening; a slip ring arranged in said openings; a brake drum formed on said slip ring, said brake drum having shoulders; and brake shoes adapted to operate on said drum, said brake shoes being arranged to positively prevent a rotation of said slip ring in one direction by engaging said shoulders and to frictionally prevent a rotation of said slip ring in an opposite direction by engagement of said brake shoes with said brake drum.

11. In a rotary machine of the class described, the combination of: a base having a base open-

- ing therein; a rotary table supported by said base, said rotary table having a table opening which aligns with said base opening; a slip ring arranged in said openings; a brake drum formed on said slip ring, said brake drum having shoulders; brake shoes adapted to operate on said drum, said brake shoes being arranged to positively prevent a rotation of said slip ring in one direction by engaging said shoulders and to frictionally prevent a rotation of said slip ring in an opposite direction by engagement of said brake shoes with said brake drum; and means for adjustably forcing said brake shoes into engagement with said brake drum.
12. In a rotary machine of the class described, the combination of: a base having a base opening therein; a rotary table supported by said base, said rotary table having a table opening which aligns with said base opening; a slip ring arranged in said openings; a brake drum formed on said slip ring, said brake drum having shoulders; brake shoes adapted to operate on said drum, said brake shoes being arranged to positively prevent a rotation of said slip ring in one direction by engaging said shoulders and to frictionally prevent a rotation of said slip ring in an opposite direction by engagement of said brake shoes with said brake drum; brake shoe rods engaging said brake shoes; bell cranks, said bell cranks having said brake shoe rods hinged thereto; and springs attached to said bell cranks, said springs being adapted to affect said bell cranks in such a manner as to bring said brake shoe rods pressurably into engagement with said brake shoes.
13. A combination as in claim 12 in which said effect of said springs on said bell cranks is adjustable.
14. In a rotary machine of the class described, the combination of: a base having a base opening therein; a rotary table supported by said base, said rotary table having a table opening which aligns with said base opening; a slip ring arranged in said openings and supported by said base; and means for positively preventing rotation of said slip ring in one direction and for frictionally preventing a rotation of said slip ring in an opposite direction.
15. In a rotary machine of the class described, the combination of: a base having a base opening therein; a rotary table supported by said base, said rotary table having a table opening which aligns with said base opening; a slip ring arranged in said openings and supported by said base; a brake drum formed on said slip ring, said brake drum having shoulders; and brake shoes adapted to operate on said drum, said brake shoes being arranged to positively prevent a rotation of said slip ring in one direction by engaging said shoulders and to frictionally prevent a rotation of said slip ring in an opposite direction by engagement of said brake shoes with said brake drum.
16. In a rotary machine of the class described, the combination of: a base having a base opening therein; a rotary table supported by said base, said rotary table having a table opening which aligns with said base opening; a slip ring arranged in said openings and supported by said base; a brake drum formed on said slip ring, said brake drum having shoulders; brake shoes adapted to operate on said drum, said brake shoes being arranged to positively prevent a rotation of said slip ring in one direction by engaging said shoulders and to frictionally prevent a rotation of said
- slip ring in an opposite direction by engagement of said brake shoes with said brake drum; and means for adjustably forcing said brake shoes into engagement with said brake drum.
17. In a rotary machine of the class described, the combination of: a base having a base opening therein; a rotary table supported by said base, said rotary table having a table opening which aligns with said base opening; a slip ring arranged in said openings and supported by said base; a brake drum formed on said slip ring, said brake drum having shoulders; brake shoes adapted to operate on said drum, said brake shoes being arranged to positively prevent a rotation of said slip ring in one direction by engaging said shoulders and to frictionally prevent a rotation of said slip ring in an opposite direction by engagement of said brake shoes with said brake drum; brake shoe rods engaging said brake shoes; bell cranks, said bell cranks having said brake shoe rods hinged thereto; and springs attached to said bell cranks, said springs being adapted to affect said bell cranks in such a manner as to bring said brake shoe rods pressurably into engagement with said brake shoes.
18. In a rotary, a base having an annular oil chamber, a shaft housing secured to said base and having an oil chamber therein communicating with said annular chamber, a shaft within said housing, a pinion on said shaft and rotating in part in the annular chamber, a gear on said table meshing with said pinion, a plurality of series of bearings all located in part in said annular chamber rotatably supporting said table on said base.
19. The combination with a table, an annular gear carried thereby, a series of bearings for said gear, a base enclosing said gear bearings between said base and table, a shaft, a pinion thereon driving said gear, of a one piece housing for said shaft having a fluid-tight connection with said base and forming with it an oil bath for said shaft, pinion and bearings.
20. In a rotary for well drilling, a bed plate, a table thereon, means forming an enclosure between said bed plate and table, a table supporting bearing between said table and said bed plate, a ring gear on said table, hold-down means in said enclosure to hold said table on said bed plate, and means for oiling said bearing and said hold-down device.
21. In a rotary drilling machine, a bed plate, a table rotatable on said bed plate, means forming an enclosure between said table and bed plate, a thrust bearing within said enclosure, a gear on said table, a pinion engaging said gear within said enclosure, means to hold said table on said bed plate, said pinion acting to circulate lubricant to said gear and said bearing, said table holding means including a hold-down ring on said bed plate engaging within a groove in said table.
22. In an oil bath rotary for well drilling, a table, a bed plate supporting said table, an upstanding rim on said bed plate, a downwardly extending annular projection on said table forming a chamber between said bed plate and said table, a gear on said table within said chamber, a bearing on said bed plate, a hold-down ring attached to said upstanding rim and arranged to hold said table on said bed plate, and a lubricating system contained within said chamber, said gear acting to deliver lubricant to said ring.
23. In a rotary drilling machine, a table, a bed plate therefor, means forming an enclosure be-

- tween said bed plate and table, a gear on said table, a pinion engaging said gear, a drive shaft for said pinion, a thrust bearing for said pinion, a hold-down ring on said bed plate, engaging said table, said pinion acting to circulate lubricant to said thrust bearing and said hold-down ring. 5
24. In a rotary for well drilling, a rotary table, a bed plate, anti-friction bearings supporting said table upon said bedplate, an oil chamber formed in said bedplate, a gear on said table, a drive shaft supported on said bedplate, a pinion on said shaft, an annular groove on said table forming a shoulder, a hold-down bearing ring attached to said bedplate and engaging said shoulder for holding said table down on said bedplate, said holdown bearing ring and said annular groove being situated inside of said oil chamber, said gear and pinion causing a circulation of 10 lubricant to said bearing. 20
25. In a rotary of the class described, the combination of a body, said body having inner and outer upwardly extending walls forming a channel, a table carried by said body, said table having a downward extension projecting inside said inner wall, and a downwardly extending lip projecting outside said outer wall, thus forming an oil chamber; an anti-friction thrust bearing supporting said table in rotation upon said body, a 15 hold-down bearing ring secured on said body and engaging a shoulder on said table for holding said table down on said body, said thrust bearing and hold-down ring bearing being disposed inside said channel. 30
35. 26. In a rotary for well drilling, a table, a bedplate, complementary parts on said bedplate and said table forming a chamber therebetween, a hold-down bearing disposed in said chamber and means of adjusting said hold-down ring on said bed plate. 40
27. In a rotary for well drilling, a table, a bed plate, complementary parts on said bedplate and said table forming a chamber therebetween, a hold-down bearing disposed in said chamber, 45 means for securing said holdown bearing to said bed plate, and means secured outside of said chamber for fastening said hold-down bearing to said bedplate. 50
28. In a rotary for well drilling, a bed plate, a table rotatable thereon, complementary parts on said table and said bed plate forming a chamber therebetween, a unitary one-piece hold-down bearing ring disposed in said chamber, and means to secure said hold-down ring to said bed plate. 55
55. 29. In a rotary for well drilling, a bed plate, a table rotatable thereon, interengaging parts on said table and bed plate forming a closed chamber therebetween, said chamber being formed with outer and inner compartments, a table gear disposed in one of said compartments and an anti-friction thrust bearing disposed in another of said compartments, and means to circulate lubricant in said chamber. 60
30. In a rotary machine of the type employed in the drilling of wells, the combination of, a base, a rotary table above said base, means on said table and base cooperating to form a closed chamber between the same, a ring gear on said table in said chamber, a drive pinion extending into said chamber and engaging said gear, bearings for said table on said base, said pinion acting in rotating to splash lubricant in said chamber to said gear and said bearings, an outwardly projecting annular shoulder on said table, a hold down ring on said base engaging above said shoulder, and anti-friction bearings between said ring and shoulder. 65
31. In a rotary machine of the type employed in the drilling of wells, the combination of, a base, a rotary table above said base, means on said table and base cooperating to form a closed chamber between the same, a ring gear on said table in said chamber, a drive pinion extending into said chamber and engaging said gear, bearings for said table on said base, a lubricant containing recess in said base below said pinion, said pinion acting to convey lubricant from said recess to said ring gear and said bearings, an inwardly projecting hold down means on said base, an outwardly projecting shoulder on said table, and anti-friction bearings between said hold-down means and said shoulder to hold said table rotatably on said base. 10 15
32. In a rotary device for well drilling, a base plate, an annular bearing race on said base, bearings thereon, a table rotatable on said bearings, an upwardly extending rim on said base, a skirt on said table cooperating with said rim to form an enclosure for said bearings, there being a lateral opening in said rim, a ring gear on said table in said enclosure, a closure member in said opening to seal the same, a shaft bearing in said member, a drive shaft in said shaft bearing, and a drive pinion on said shaft within said enclosure positioned to engage said ring gear. 20 25 30
33. In a rotary device for well drilling, a base plate, an annular bearing race on said base, bearings thereon, a table rotatable on said bearings, an upwardly extending rim on said base, a skirt on said table cooperating with said rim to form an enclosure for said bearings, an inner annular wall on said base inside said bearings to form a lubricant channel between said rim and wall, a ring gear on said table within said enclosure, a drive shaft projecting through an opening in said rim, a pinion thereon engaging said ring gear, a closure for said opening about said shaft and shaft bearings in said closure for said shaft. 35 40
34. In a rotary device for well drilling, a base plate, an annular bearing race on said base, bearings thereon, a table rotatable on said bearings, an upwardly extending rim on said base, a skirt on said table cooperating with said rim to form an enclosure for said bearings, an inner annular wall on said base inside said bearings to form a lubricant channel between said rim and wall, a ring gear on said table within said enclosure, a drive shaft projecting through an opening in said rim, a pinion thereon engaging said ring gear, a closure for said opening about said shaft and shaft bearings in said closure for said shaft. 45 50
55. 35. In an oil bath rotary for well drilling, including a base, a table rotatable thereon, an enclosed holdown bearing for said table on said base and means for lubricating the same. 60
36. In an inclosed oil bath rotary for well drilling, including a base, a table rotatable thereon, an enclosure between said table and said base, a table hold down bearing within said enclosure, and means in said enclosure for lubricating said hold down bearing. 65
37. In an oil bath rotary for well drilling, an enclosure within which is located a table hold down bearing, and means for excluding foreign matter from said enclosure. 70
75. 38. In a rotary machine for well drilling, the combination of a base, a rotary table, a support- 75

ing bearing assembly on said base for rotatably supporting the table, an inner annular upstanding wall in the base enclosing the supporting bearing assembly circumferentially to define a 5 separate lubricant chamber for the bearing, an outer upstanding annular wall on the base cooperating with the table to define a separate lubricant chamber between the inner and outer annular walls, an opening in said outer wall below 10 the upper edge thereof and drive means insertable through said opening to rotate within the outer lubricant chamber and drive the table.

39. In a rotary machine of the type employed in the drilling of oil wells, the combination of: a 15 base having an upstanding wall; a rotary table cooperating with said upstanding wall for providing a lubricant chamber, a support inwardly of said upstanding wall within said chamber; a bearing on said support for rotatably supporting 20 said rotary table; drive means for driving said table including a ring gear secured to said table and a pinion gear, both of which are within said chamber, said pinion gear delivering lubricant to said ring gear; and a hold down ring above the oil 25 level in the lubricant chamber for receiving lubricant dropping from said ring gear.

40. In a rotary machine of the type employed

in drilling oil wells, the combination of: a base having an annular oil channel and an annular support inwardly of said oil channel; a bearing supported on said support; a table supported on said bearing, said table cooperating with said base to form a closed chamber in which said annular oil channel, said support, and said bearing are located; a ring gear secured to said table and situated in said chamber above said oil channel; a rotatable drive pinion serving to supply oil to said ring gear, said oil dropping downwardly in said chamber from the teeth thereof; and a hold down ring intercepting said oil falling in said chamber. 10

41. A rotary machine of the type employed in the drilling of oil wells, the combination of: a base 15 having an annular oil channel; a rotary table above said base and cooperating therewith to form a closed chamber in which said oil channel is located; a bearing in said chamber for rotatably supporting said table; a ring gear on said table 20 within said chamber; means for supplying said ring gear with oil, a hold down device in said chamber, said machine being constructed so that the oil from said ring gear will serve to lubricate said hold down device for said table. 25

FREDERIC W. HILD.
